UNITED STATES PATENT OFFICE.

WILLIAM S. GODWIN, OF CLEVELAND, OHIO.

STREET-RAILWAY CONSTRUCTION.

1,349,451.

Specification of Letters Patent. Patented Aug. 10, 1920.

Application filed February 14, 1919. Serial No. 277,064.

To all whom it may concern:

Be it known that I, WILLIAM S. GODWIN, a citizen of the United States, residing at Cleveland, in the county of Cuyahoga and State of Ohio, have invented certain new and useful Improvements in Street-Railway Construction, of which the following is a specification.

This invention relates to improvements in street railway construction, and more particularly to a between-rails paving guard.

The primary object of the invention is to provide a paving guard which, with the rail, forms a groove to accommodate the flange of the wheel, the guard being held in place by the paving.

A further object of the invention is to provide a guard which is unattached to the rail base, so that the vibrations of the rail will not be imparted to the paving, thereby reducing injury to the paving adjacent the rails to a minimum.

A still further object of the invention is to provide a rail filler having a strip of elastic material interposed between the head of the rail and the filler, to prevent the shock of traffic from shattering the filler, the arrangement of the filler with relation to the guard being such as to prevent also the injurious effects of water seeping in under the rail tread above the filler.

The standard T-rail has proven, by service, to be preferable to the girder-tram rail, or the girder-groove rail. The first cost of the standard T-rail, also the maintenance cost, is considerably less than the cost of the tram-rail and the groove-rail. T-rails are not, however, satisfactory in paved streets, as their use does not permit of the necessary smooth continuity of the pavement. I have therefore, devised the construction of guard illustrated, which when used in connection with the standard T-rail, provides the necessary groove-way for the wheel flange and also the necessary protection for the paving, the completed construction permitting the desired surface smoothness, and a desired condition in all respects with regard to team traffic that is incident to the use of the ordinary girder-groove rail.

Another object of the invention is to provide a convenient form of anchor which, coöperating with the peculiar guard construction, maintains the guard firmly in

place, in the paving, the construction being such that the anchor or anchors not only serve to keep the guard firmly in place, but at guard joints, serve to keep the guard in perfect alinement, all as will appear in the course of the following description.

In the drawings illustrating the invention,

Figure 1 is a section of a portion of a street or roadway adjacent the rail;

Fig. 2 is a side view of the guard, there being shown the ends of two guards in proper relation to each other, the anchors in this view being slightly raised in order to show more clearly their contour;

Fig. 3 is a sectional view of a street or roadway, showing a T-rail construction with modified form of guard and anchor, and

Fig. 4 is a similar view, with still another modified form of guard and anchor;

Fig. 5 is a detail section of a portion of a street or roadway, showing another form of guard, and

Fig. 6 is an elevation showing the flat side of the guard or the anchor portion.

Referring to the drawings, the numeral 1 designates the cross-tie, which may be of wood or metal and of any suitable or approved construction. This tie rests upon a suitable foundation such as soil, ballast, concrete, etc. The numeral 2 designates a standard T-rail with the base resting on the tie 1.

The numeral 3 designates the paving base, preferably of concrete, and the numeral 4 the wearing surface of asphalt or any other suitable material. The numeral 5 designates a paving guard, which is made in suitable lengths, and which extends parallel with the rail and is provided at intervals, with anchors 6, which are embedded in the concrete, to hold the guard 5 in place, the guard forming a boundary for the wearing surface of the street, and being so positioned with regard to the rail, as not to have the vibrations of the rail transmitted thereto.

This construction is fully described and claimed in Patent Number 1,246,907, granted November 17, 1917, and has to do with paving construction outside the rails, and need not therefore, be further referred to in this application, since in this application the invention resides in the "between-rails" construction, which will be now described in detail.

The numeral 7 designates the roadway base, preferably of concrete, or the same material as that which composes the paving base on the outside of the rails. This base 5 is formed between the rails and extends substantially for the entire distance between them, and supports a wearing surface 8 of asphalt, concrete, blocks, or other suitable material. The numeral 9 designates the 10 metallic guard, which is made in sections of very considerable length. The under side of the guard, at a point farthest from the rail, is provided with a longitudinal groove 10, and a downwardly extending vertical 15 portion 11. The numeral 12 designates a yoke-shape anchor, preferably round in cross section, and adapted to be received in the groove 10 of the guard. At intervals, the guard is slit or cut as indicated at 13, the 20 cut portions being adapted to be bent under the horizontal portion of the yoke, to firmly secure the guard and anchors together. The downwardly extending arms of the anchors are embedded in the concrete base 7 and the 25 base, adjacent to the rails is so shaped as to completely fill in under the downwardly curved or projecting flange 14 of the guard, this flange of the guard being so shaped and positioned relative to the rail, as to provide 30 a groove 15 for the flange 16 of the wheel. The rail is provided on both sides with a filler of suitable material, preferably concrete, as indicated by the numerals 17, and 18, the outer faces of the filler being in line 35 with the outer edges of the tread or head of the rail, as shown, and extend to the base of the rail. Interposed between the tops of the fillers and the underside of the tread, are strips of asphalt or other elastic material 40 19, which permit of the vertical expansion and contraction of the filler, thus eliminating the likelihood of cracking or disintegration of the fillers, due to temperature variations, and vibrations due to traffic. They 45 also absorb the shock of traffic, and prevent chipping of the filler.

The edge of the guard adjacent the rail is provided with a short downwardly extending flange 20, which rests snugly against 50 the face of the rail filler.

Attention being particularly called to Fig. 2, it will be noted that an anchor is attached to the guard, near the ends of the guard, there being provided at or near the ends, the 55 ears 13, which, as before suggested, are bent under the horizontal portion or top portion of the anchor, thereby causing the anchors to serve, not merely as anchors by which the guard is held firmly in place by the concrete base, but also to keep the guard sections in true alinement. It will be further understood that several of these anchors, depending upon the length of the guard sections, are provided for each guard, there 60 being provided the necessary ears at inter-

vals to embrace the upper portion of the anchors.

In constructing the portion of the pavement adjacent to the rail, the guard is first placed in position adjacent to the rail and 70 the concrete is then formed under the guard, and then the wearing surface of asphalt, or other suitable material, is placed on the base, to the desired thickness, until its upper surface or line is flush with the upper 75 face of the guard.

The construction is one in which it will be noted that the rail rests entirely upon the cross-tie, as in my patent hereinbefore referred to, and that the base of the "between-rail" portion of the roadway or the concrete 80 7 is in no way attached to the cross tie, consequently, vibrations of the tie, due to traffic, will not be transmitted to the guard, and consequently the paving adjacent to the guard will not be injured, as in cases where the guard is tied to the cross-tie, or to plates or other members carried by the cross tie, or rail.

It will be noted that the lower portion of 90 the guard, adjacent the rail, has its upper surface about on line with the filler 18, which is interposed between the strip of elastic material 19 and the rail base on the guard side of the rail, thus preventing 95 water, which may accumulate in the groove formed by the rail and paving guard, from seeping down between the filler and the concrete base 7.

It will be understood that the anchor arms 100 12 may be twisted or provided with roughened portions if necessary, to afford a firm hold in the concrete base.

Referring to the modifications shown in Fig. 3, the numeral 21 designates a modified 105 form of guard, which, as in the case of the guard just described, is made in sections of convenient length, but this guard is intended for use in street construction where the paving between the rails is not brought to 110 the level of the top of the tread of the rail. These guards in such construction are provided centrally with a downwardly extending flange or web 22, which extends into the concrete base 7, and at intervals anchors 23 are formed or attached, either by welding, or any other suitable means. These anchors may be flat pieces, twisted as indicated, so as to get a firm hold in the concrete base. As in the case of the preferred 115 form of guard, or the groove rail construction, the anchors are not in any way connected with the cross tie, consequently the vibrations of the rail, due to traffic, are taken up by the cross tie and not imparted 120 to the guard.

In Fig. 4, still another form of paving guard is shown, this being a guard made in sections of convenient length, with flat upper surface, and downturned flanges 24 and 130

25, to which anchors 26 and 27 are attached or formed at intervals in the same manner as that described in connection with the form shown in Fig. 3, and it will be noted 5 that in this form also, the anchors are embedded in the concrete, and have no connection whatever with the cross ties.

In this construction, the strips of elastic material above the rail fillers are employed 10 and the bottom of the strips on the guard side of the rail, are in line with the top surface or tread portion of the guards, thus, as in the preferred form, preventing water from seeping in above the fillers.

15 Referring to Figs. 5 and 6, the guard 28 is formed with a continuous flat vertical portion 29 slit at opposite angles, as indicated at 30, to form ears 31 which are bent in staggered order, which formation enables 20 the concrete to fill in between the ears, and thus more firmly lock the guard in place.

Having thus fully described my invention, what I claim is:—

1. A between rail paving guard, having a 25 downwardly depressed top which in connection with a T-rail, forms a flangeway or trough, said guard being carried by the paving and unattached to the rail or rail support, and free from the material immediately adjacent to the rail.

2. A between rail paving guard that forms in connection with the T-rail, a grooveway, said guard being unattached and free from the rail or rail support, but 35 attached to the paving that is free from the rail.

3. A between-rail paving guard for use in connection with a T-rail, comprising a metallic member adapted to extend longitudinally of the rail outside the tread portion thereof and below the tread of the rail to allow for the flange of a car wheel, means for anchoring the guard in the paving between the rails, said guard also serving as 45 a boundary for the paving between the rails.

4. A between-rail paving guard for use in connection with a T-rail, comprising a metallic member adapted to extend longitudinally of the rail, and formed with a down- 50 turned flange, an anchor secured to said flange and adapted to be embedded in the paving between the rails to hold the guard in place, said anchor being also formed with a portion adapted to be positioned below the 55 tread of the rail, to allow for the flange of a wheel.

5. A between-rail paving guard for use in connection with a T-rail, comprising a metallic member extending longitudinally of 60 the rail, and formed with a downwardly extending flange cut at intervals to form ears adapted to be bent to embrace an anchor, an anchor embraced by said ears, the anchor being adapted to be embedded in the 65 paving between the rails to hold the guard

in place, said guard being also formed with a portion adapted to lie below the tread of the rail, to allow for the flange of a car wheel.

6. A between-rail paving guard for use in 70 connection with a T-rail, comprising a metallic member provided with a downturned flange cut at intervals to form ears adapted to be bent to embrace the upper portion of an anchor, and a portion adapted to extend 75 toward the rail and below the tread thereof, to allow for the flange of a car wheel, an anchor embraced by said ears and adapted to be embedded in the paving between the rails, said guard also serving as a boundary for 80 the paving surface adjacent the rail.

7. A between-rail paving guard for use in 85 connection with a T-rail, comprising a metallic member adapted to extend longitudinally of the rail inside the tread of the rail and below the top of the tread, an anchor formed with a portion extending longitudinally of the rail and secured to the paving and with downwardly extending arms adapted to be embedded in the paving between the rails.

8. In a street railway construction, in combination, a T-rail, a rail support, a concrete foundation above the rail support between the rails, and having its inner surface 95 adjacent to the rail outside the edges of the rail head, a pavement on the concrete base, a longitudinally extending guard on the inside of the rail, and having a portion lying below the tread of the rail and outside the 100 inner edge of the tread, anchors secured to the guard, and embedded in the concrete foundation to hold the guard in place, said guard also serving as a boundary for the wearing surface of the pavement, adjacent 105 the rail.

9. In a street railway construction, in combination, a T-rail, a support for the rail, a concrete foundation extending above the rail support and between the rails and having its inner surface adjacent the rail outside of the edges of the rail head or tread, a pavement on the concrete base, a longitudinally extending metallic guard formed with a downturned flange cut at intervals to form ears, adapted to be bent to embrace an anchor, an anchor embraced by said ears and embedded in the concrete foundation to hold the guard in place, said guard also having a portion lying outside 115 of the inner edge of the tread and below the same to allow for the flange of a wheel, the guard also serving as a boundary for the pavement adjacent the rail.

10. In a street railway construction, in 125 combination, a T-rail, a rail support, a concrete foundation above the rail support and between the rails, a longitudinally extending guard, inside the tread of the rail and having a portion below the tread to allow 130

for the flange of a car wheel, anchors secured to the guard and embedded in the concrete foundation for holding the guard in place.

- 5 11. In a street railway construction, in combination, a T-rail, a rail support, a concrete foundation extending above the rail support and between the rails, a longitudinally extending guard having a downwardly extending flange cut at intervals to form ears adapted to be bent to embrace an anchor, a plurality of anchors formed with longitudinal portions embraced by the guard ears and having arms embedded in

the concrete foundation to hold the guard 15 in place, said guard being formed also with a portion extending below the tread of the rail to form with the rail a groove to allow for the flange of a car wheel, and a pavement on the concrete foundation whose 20 outer edge is bounded by the guard.

In testimony whereof I affix my signature in presence of two witnesses.

WILLIAM S. GODWIN.
